BRACKET RECEPTACLE

Lawrence Milton Hobson, Portland, Oreg

Application January 29, 1951, Serial No. 208,411

3 Claims. (Cl. 211—89)

11

This invention relates to an L-shaped bracket for attachment to the plane vertical surface of a kitchen wall, cabinet door, or the like, therewith to bound and to define a shelf-like receptacle for receiving and holding cook books, pot holders, paper napkins, used paper sacks, or any other flat household items which people wish to save and to have readily accessible, which would otherwise be stored in drawers and shelves of a kitchen, bathroom, or hallway.

The motto of the neat modern housewife is, "a place for everything and everything in its plate." In furtherance of this motto, modern homes are equipped with large numbers of closets, cabinets, drawers, and shelves in which and upon which the thousand-and-one items of daily living are kept. Still, in spite of the large number of storage areas so provided, flat household items and equipment continue to accumulate in odd places about the house. Over the years, such an accumulation exceeds the household storage capacity and creates an unsightly clutter in corners, on tables and in odd places. This is a source of never ending irritation to the neat housewife. In balm of this irritation, I have turned my inventive thoughts and experimentation toward the provision of added, neat and inexpensive shelf and storage facilities for use in the kitchen, hall, bathroom or elsewhere about the home.

By way of example, an exploratory look about the kitchen of a typical home will reveal many small, out-of-the-way areas which are available as storage installation spaces. Thus, even though the kitchen walls may be covered substantially by cabinet, shelf, and drawer structure, small vertical areas behind the stove, above the sink, beside the refrigerator, against cabinet doors, and elsewhere, conveniently are available. Accordingly, my novel shelf-like receptacle primarily is intended for installation in such areas. Furthermore, it is my intention to provide a receptacle which is susceptible of easy installation so the housewife herself may install the same.

To this end, one object of my invention is to provide an oblique, L-shaped bracket adapted to be secured to the plane vertical surface of a wall, cabinet door, or the like, to bound and define therewith a receptacle of right triangular cross section. The integral body member of my bracket includes a floor portion defining one leg of the triangle, a resilient holding plate defining the hypotenuse, and a flange portion pendent from the floor and parallel the plane surface of the wall for ease in attaching the bracket. Thus, when mounted, the wall or other vertical surface

forms the other leg of the triangle cross section whereby household items are held securely in place between this surface or leg and the triangle hypotenuse.

5 It is a further object of my invention to provide, for a receptacle of this type, a holding plate which is resilient and which is biased toward engagement with the wall surface whereby objects resting on the floor portion yieldably will be gripped and will be pressed against the wall by the upper portion of the plate.

Yet another object of my invention is to provide a small L-shaped retention bracket pendent from the aforementioned floor member and yield-

15 ably pressed in engagement with the outer surface of the holding plate. This retention bracket serves two functions in that it presses against the holding plate in aid of the grip or yieldable bias thereof and it serves as a second, somewhat 20 smaller, receptacle to hold similar, but smaller, items against the outer surface of the plate. Thus, smaller household items do not become lost or obscured from view as they would if held by the large bracket receptacle.

25. These and other objects and advantages of my invention will be set forth in the following detailed description taken in conjunction with the accompanying drawings, wherein:

Fig. 1 is a front elevation of my receptacle showing the relative sizes of the large resilient holding plate and the small retention bracket, the latter being pressed against the outer surface of the former:

Fig. 2 is a side view showing the empty receptacles as they appear when mounted against a plane vertical surface such as a wall, cabinet door, or the like; and

Fig. 3 is a side view similar to Fig. 2 but indicating the manner in which several common, flat household items are held against the wall by the large, resilient holding plate and against the outer surface of the holding plate by the small retention bracket.

Toward the provision of a simple, inexpensive receptacle structure, I prefer to assemble my device from two oblique, L-shaped bracket elements 1 and 2. The first such element is a large bracket member 1 having a holding plate portion 11, a floor portion or member 12, a pendent flange portion or member 13, and a protruding finger grip portion 14. The second such element includes a small, L-shaped retention bracket 2 having a hold portion 21, a floor portion 22, a securing flange 23, and a convex grip portion 24. The large bracket element 1 is adapted for ready attachment to any

plane vertical surface such as the wall or cabinet door indicated at 3. To this end, the pendent flange member 13 is provided with apertures 15 through which screw elements 16 may be inserted for anchor-like contact with the wall. Similarly, the small bracket element 2 is made pendent from the floor member 12 and is secured thereto by means of rivets 25 fastening the securing flange 23 to the floor member 12.

Within the scope of my inventive concept, any lightweight, durable material such as sheet aluminum, steel, or plastic may be utilized. In view of the uses to which my bracket is to be put, however, it is desirable that the holding plate 11 and hold portion 21 be resilient and flexible in order to grip and frictionally to engage flat household items. In the preferred embodiment, the bracket elements 1 and 2 are formed from high-tensile strength, spring aluminum having a satin finish body of shiny appearance. Such a material and such a finish possess the advantage of having an attractive eye appeal complementary to the color scheme of most kitchens and bathrooms.

In use, the large bracket element 1 is secured to the plane vertical surface of a kitchen or bathroom wall, cabinet door, or the like 3 by means of the screws 16. When secured in place, the bracket and wall, together, bound and define a right triangular cross section as indicated in Fig. 2. Thus, the wall surface 3 is one leg of the triangle, the floor 12 is another leg and the holding plate 11 is the triangle hypotenuse. Further, it is to be noted, the small bracket element 2 defines, together with the large bracket element 1, a somewhat similar triangle cross section (see Fig. 2). Thus, the hold portion 21 is the hypotenuse and the floor portion 22 and holding plate 11 are the legs of this second triangle. It is these triangle cross sections which lend to my receptacles a superior ability to grip and hold objects deposited therein.

By way of example, I have shown both of the bracket elements in operative position with respect to several flat household items in Fig. 3. The items so held may be pot holders, as indicated at 4, or they may be small tablets of the type indicated at 5. Optionally, of course, a large variety of items will suggest themselves to the housewife. For example, the large bracket element 1 efficiently will grip and hold cook books, paper napkins, newspapers, used paper sacks, or a phone book. The small bracket 2, on the other hand, will hold recipe notes, pencils, coupons, stamps, or other, somewhat smaller household items. In any event, the exemplary pot holders 4 may be inserted by gripping the protruding finger grip portion 14 between the thumb and forefinger to pull the resilient holding plate 11 away from the wall. Thereafter, the pot holders 4 are dropped into the receptacle until they rest on the floor member or portion 12. When the finger grip portion 14 is released, the inherent resiliency of the holding plate portion 11, as aided by the triangle cross section structure, forces the upper surface of the plate against the pot holders 4 securely to grip and hold the same in place against the wall 3. If, at this time, the small bracket 2 is not in use, the inherent spring-like resiliency of the hold portion 21 aids the resiliency of the holding plate 11 in gripping the pot holders 4. If, on the other hand, other items, such as the small tablet 5, are placed between the holding plate 11 and the hold portion 21, these other items, also, will be held tightly in place.

In service to the objects of my invention, it will be noted that the absence of side portions, the use of thin resilient sheet metal, the use of a triangular, structural disposition of elements, and the minimum use of fastening devices such as rivets, screws, and handles, all are directed toward the attainment of an inexpensive yet efficient structure. The relative small size and novel shape of my receptacle is of further utility in allowing the housewife to utilize the empty vertical areas presented by the wall spaces behind the stove, above the sink, beside the refrigerator, or against cabinet doors. Accordingly, each of the structural features of my invention are directed toward elimination of the unsightly clutter which accumulates in corners, on tables, and in odd places and toward the release of other shelf and drawer spaces for the truce attainment of the housewife's motto, "a place for everything and everything in its place."

I claim:

1. An oblique L-shaped bracket for attachment to the plane surface of a wall, cabinet door, or the like to bound and to define therewith a receptacle of right triangular cross section, comprising an integral elongated body having a floor member defining one leg of the triangle, a holding plate defining the hypotenuse, and a flange member perpendicular to and pendent from the

30 floor member, said flange member being pierced by attachment apertures for mounting said bracket, and a small L-shaped retention bracket carried by said floor member oblique to said holding plate and defining with the latter a second 35 receptacle, said retention bracket terminating in abutment with said holding plate.

2. A bracket adapted to be mounted upon a plane surface to bound therewith a receptacle of triangular cross section, comprising an integral elongated body having a floor member defining one leg of the triangle, a holding plate means defining the hypotenuse, and a flange member perpendicular to said triangle leg for attaching the bracket to said plane surface, said holding plate means being resilient, yieldably to press against said plane surface at a point spaced from said floor member, and a small L-shaped retention bracket carried by said floor member oblique to said holding plate and defining therewith a second receptacle of similar cross section and similar resiliency, said resilient retention bracket pressing against said holding plate means to aid the press of the latter against said plane surface.

3. An oblique L-shaped bracket adapted to be mounted upon the plane surface of a wall, cabinet door, or the like to bound therewith a receptacle of right triangular cross section, comprising an integral elongated body member having a floor portion adapted to lie horizontal to define one leg of the triangle, a holding plate portion defining the triangle hypotenuse, and a flange portion perpendicular to said triangle leg, said flange portion having means for attaching the bracket to

60 said plane surface to prevent lateral movement of the body member relative to the plane surface, said holding plate being resilient, yieldably to press against said plane surface at a point spaced from said floor member thereby frictionally to engage objects deposited in the receptacle, said holding plate terminating in a protruding finger grip portion by means of which said plate may be pulled away from said plane surface, and a small L-shaped retention bracket carried by said 65 floor portion oblique to said holding plate and

defining therewith a second receptacle of similar cross section, said retention bracket being dependent from said floor portion and being resilient, yieldably to press against the outer surface of said holding plate intermediate the margins and in aid to the said yieldable press thereof.
